GLOW STARTING RELAY FOR
FLUORESCENT LAMPS

Charles H. Hodgkins, Fairfield, Conn., assignor
to The Bryant Electric Company, Bridgeport,
Conn., a corporation of Connecticut

Application June 14, 1945, Serial No. 599,333

4 Claims. (Cl. 315—100)

1

The present invention relates to fluorescent lamp circuits and particularly to a starting relay or switch therefor of the type now commonly referred to as the "no-blink" which operates to prevent intermittent repetitious flashing of a fluorescent lamp when the latter becomes defective, and constitutes an improvement on the structure such as shown in Patent No. 2,355,476, issued August 8, 1944, to Roy M. Smith and John R. Steegstra and assigned to the same assignee as the present invention.

Starting relays of this general type are now well known in the art but have heretofore been of the resistance heater type in their entirety or of the combined glow switch and thermal type. In the former type normal as well as "lock-out" operation are dependent upon the heat generated by current flow through one or more resistance elements while in the latter type only the "lock-out" operation utilizes the heat generated by a resistance. Since both types are contained within a metallic or plastic casing which is closed to the atmosphere substantial heat is accumulated therein particularly from prolonged retention of the relay in the "lock-out" position of the relay.

Moreover, these resistance heating elements are necessarily of small size due to space requirements and because of the wattage required for their operation are too frequently subject to deterioration and change in their ohmic value after sustained operation for prolonged periods of time in "locking-out" a defective lamp which not only changes the operating characteristics of the relay but greatly shortens its useful life.

It is accordingly an object of the present invention to provide a starting relay for fluorescent lamps of the "no-blink" or "lock-out" type and wherein a resistance heater unit is unnecessary for its operation.

Another object of the present invention is the provision of a "no-blink" starting relay for fluorescent lamp wherein operation is dependent upon a glow discharge in a vitreous container and thus very little extrinsic heat is developed during any phase of its operation.

Still further objects of the present invention will become obvious from the accompanying drawing wherein:

Figure 1 is a schematic illustration of the customary fluorescent lamp circuit and showing the

2

starting relay of the present invention during one phase of its normal operation.

Figure 2 is an entirely schematic view similar to Fig. 1 showing the starting relay during another phase of its normal operation.

Figure 3 is a schematic view similar to Fig. 2 but showing the starting relay of the present invention in still another phase of its operation.

Figure 4 is a schematic illustration similar to 10 the preceding figures but showing the relay of the present invention in its "lock-out" position to prevent blinking of the lamp in the event the latter becomes defective.

Figure 5 is a cross-sectional view of the 15 complete starting relay for attachment to the customary socket.

Referring now to the drawings in detail, and particularly to Fig. 1, a fluorescent lamp 5 is 20 therein shown provided with a pair of thermionic electrodes 6 and 7. One end of the electrode 6 is connected to one side of the supply source L1, of the customary domestic potential of 115-230 volts, through an inductance element 8 and main line switch 9, while one end of the electrode 7 is connected to the other side of the supply source 25 L2. The series heating circuit is completed by the starting relay, shown generally at 10, which connects the remaining ends of the thermionic electrodes 6 and 7 together.

30 By reference now to Fig. 5 it will be seen that the starting relay 10 comprises a casing or housing 12 of metal or plastic enclosing the various elements and provided with a pair of terminals 13 and 14 for engaging the customary socket.

35 Since the elements within the casing 12 are shown on a larger scale and schematically in the remaining figures reference may be had thereto.

As shown in Fig. 1, the relay 10 comprises a 40 glow switch 15 of the usual construction now well known in the art and of the type shown and described in Patent No. 2,228,210, issued January 7, 1941, to R. F. Hays, Jr. Briefly stated, such glow switch 15 comprises an envelope provided with an ionizable medium therein at a suitable pressure and having a pair of normally spaced electrodes 16 and 17, one of which 16 is a bimetallic element deflectable under the heat generated by the ensuing glow discharge into contact with the other electrode 17. A radio frequency suppressing condenser 18 is also housed within the casing 45 50

12 and is connected directly to the socket terminals 13 and 14.

In addition, a further glow relay 19 is housed within the casing 12 which comprises a vitreous envelope 20 provided with an ionizable medium therein at a suitable pressure and corresponding to that within the glow switch 15. As will be noted, the glow relay 19 is provided with two stationary electrodes 22 and 23 and a U-shaped bimetallic electrode 24 similar to the bimetallic electrode 16 of the glow switch 15. However, in this glow relay the bimetallic electrode 24 is normally in contact with the stationary electrode 23, as shown in Figs. 1, 2 and 3, which thus completes the series heating circuit to the lamp electrodes 6 and 7 upon operation of the glow switch 15.

When the main switch 9 is closed substantially the full voltage of the supply source L1, L2 is impressed across the normally spaced electrodes 16 and 17 of the glow switch 15 since the electrodes 23 and 24 of the glow relay 19 are normally in engagement with each other. A glow discharge, as shown in Fig. 1, accordingly ensues in the glow switch 15 with heating and attendant deflection of its bimetallic electrode 16 into engagement with the stationary electrode 17. This short-circuits the discharge as shown in Fig. 2 with the result that the bimetallic electrode begins to cool and separates from the stationary electrode 17.

At the instant of separation a high voltage surge is induced across the lamp electrodes 6 and 7 by the inductance 8 which initiates a discharge in the lamp 5, as shown in Fig. 3. Once the discharge is started in the lamp 5, the voltage drop across the lamp is such that the voltage then impressed across the electrodes 16 and 17 of the glow switch 15 is insufficient to again initiate a glow discharge until after extinguishment of the lamp. The cyclic operation of the glow switch 15 as above described requires a matter of only a few seconds and if for any reason the discharge is not initiated in the lamp 5, the glow switch 15 continues its cyclic operation because the voltage across its electrodes 16 and 17 is always high enough to re-establish a discharge, until the lamp actually starts.

However, should the lamp become defective, such as by deactivation of the electrodes or the like, the continued cyclic operation of the glow switch 15 in a futile attempt to start the lamp causes a continuous glowing of the lamp electrodes followed by periodic flashing which becomes a constant annoyance. To eliminate this undesirable condition, the glow relay 19 then operates after a short interval of cyclic operation of the glow switch 15.

It will be noted that during the cyclic operation of the glow switch 15, in the manner above described, the electrodes 23 and 24 of the glow relay 19 have remained in contact with each other. However, each time a glow discharge is initiated in the glow switch 15, a simultaneous glow discharge also occurs in the glow relay 19 between its stationary electrode 22 and the bimetallic electrode 24, as shown in Fig. 1. Since the stationary electrode 22 is connected to the terminal 13 through a low resistance 25, however, the current flowing through the discharge between the stationary electrode 22 and bimetallic electrode 24 is much less than that across the glow discharge in the glow switch 15, so that the discharge in the glow relay 19 must continue for a longer period of time to heat the bimetallic elec-

trode 24 than is required in the glow switch 15. As a result, during normal operation of the glow switch 15, the ensuing simultaneous glow discharge between the electrodes 22 and 24 of the glow relay 19 has no effect on the operation of the latter. Also since the resistance 25 is of relatively low ohmic value substantially little heat is generated thereby.

Upon the continued cyclic operation of the glow switch 15 beyond a reasonable number of operations because of failure of the discharge lamp 5, the simultaneous discharge in the glow relay 19 finally heats the bimetallic electrode 24 of the latter causing it to deflect away from its stationary contact 23, as shown in Fig. 4. Should this require too great a time lapse, it may be desirable in some instances to make the electrode 23 of a high resistance contact material, such as carbon or the like, to develop heat and assist the intermittent glow discharge occurring simultaneously with the discharge in the glow switch 15, in causing deflection of the bimetallic electrode 24 of the glow relay 19.

Separation of these electrodes 23 and 24 and the engagement of the bimetallic electrode 24 with stationary electrode 22 immediately short-circuits the glow switch 15 so that it no longer operates and the full available voltage is impressed across the stationary electrodes 22 and 23 of the glow relay 19. The discharge is thus not extinguished in the relay 19 upon separation of the electrodes 24 and 23 but continues between the two stationary electrodes thus continuing to heat the bimetallic electrode 24, which maintains it separated from the stationary electrode 23. Moreover, the ohmic value of the resistance 25 is such that the formation of an arc discharge is prevented and only sufficient current flows in the resulting glow discharge between the electrodes 22 and 23 to maintain the bimetallic electrode 24 floating between the electrodes 22 and 23 or in contact with the electrode 22, as shown in Fig. 4, during the "lock-out" or "no-blink" operation of the relay as shown by this latter figure. When the circuit is interrupted either by opening of the main line switch 9 or replacement of the defective lamp 5, the relay 10 is automatically restored to normal operating condition. If desired the resistance 25 may be dispensed with and the bimetallic electrode 24 of the glow relay made sufficiently massive so that the glow discharge requires substantially the same period of time as when the current is limited by the resistance 25, before the bimetallic electrode 25 deflects and disengages the electrode 22. However, as above noted, it is preferable to employ the resistance 25 not only to provide the desired time delay by limiting the current but also to prevent the ensuing glow discharge in the glow relay 20 from deteriorating into an arc discharge.

It thus becomes obvious to those skilled in the art that a starting relay for fluorescent lamps is herein provided which is of the "no-blink" type and wherein a glow relay in combination with a glow switch is employed which operates after the lapse of a suitable period of repetitious operation of the glow switch in a futile attempt to start a defective lamp, to prevent blinking of the lamp. Moreover, by the utilization of such glow relay, the necessity for a resistance heater is eliminated, thus avoiding appreciable extrinsic heat. Also the operating characteristics of such glow relay remain substantially uniform throughout useful life which does not occur with the em-

ployment of resistance heaters in the thermal relays of the prior art.

Although one specific embodiment of the present invention has been shown and described, it is to be understood that still other modifications thereof may be made without departing from the spirit and scope of the appended claims.

I claim:

1. A relay unit for starting and operating a discharge lamp provided with a filamentary electrode and for preventing flashing thereof upon such lamp becoming defective comprising a casing, a glow switch disposed in said casing comprising an envelope having a gaseous atmosphere therein and provided with a pair of electrodes one of which is a bimetallic element and adapted to be connected to the filamentary electrode of the discharge lamp and cyclically operable upon the application of a potential thereto and to the discharge lamp to establish a glow discharge in said glow switch with attendant heating of its bimetallic element and movement thereof into contact with the other electrode of said pair to repetitiously complete a starting circuit to the lamp until a discharge occurs therein, and a glow relay disposed in said casing comprising an envelope having a gaseous atmosphere therein and provided with a pair of electrodes one of which is a bimetallic element and normally engaging each other to complete a circuit to said glow switch, and having another electrode for supporting a glow discharge with one of the electrodes of said pair simultaneously with the occurrence of a cyclic discharge in said glow switch in a futile attempt to start a defective lamp to cause heating of its bimetallic element and disengagement thereof from the other electrode of said pair with attendant short-circuiting of said glow switch to prevent further cyclic operation of the latter and repetitious flashing of the defective lamp.

2. A relay unit for starting and operating a discharge lamp provided with a filamentary electrode and for preventing flashing thereof upon such lamp becoming defective comprising a casing, a glow switch disposed in said casing comprising an envelope having a gaseous atmosphere therein and provided with a pair of electrodes one of which is a bimetallic element and adapted to be connected to the filamentary electrode of the discharge lamp and cyclically operable upon the application of a potential thereto and to the discharge lamp to establish a glow discharge in said glow switch with attendant heating of its bimetallic element and movement thereof into contact with the other electrode of said pair to repetitiously complete a starting circuit to the lamp until a discharge occurs therein, and a glow relay disposed in said casing comprising an envelope having a gaseous atmosphere therein and provided with a pair of electrodes one of which is a bimetallic element and normally engaging each other to complete a circuit to said glow switch, and having another electrode for supporting a glow discharge with one of the electrodes of said pair simultaneously with the occurrence of a cyclic discharge in said glow switch in a futile attempt to start a defective lamp to cause heating of its bimetallic element and disengagement thereof from the other electrode of said pair with attendant short-circuiting of said glow switch to prevent further cyclic operation of the latter and repetitious flashing of the defective lamp, and means within said casing and connected with said another electrode to limit

the current in the glow discharge occurring in said glow relay to cause a slight delay in the disengagement of the electrodes of said pair until said glow switch has cyclically operated for a sufficient period of time to start a lamp free from defects.

3. A relay unit for starting and operating a discharge lamp provided with a filamentary electrode and for preventing flashing thereof upon such lamp becoming defective comprising a casing, a glow switch disposed in said casing comprising an envelope having a gaseous atmosphere therein and provided with a pair of electrodes one of which is a bimetallic element and adapted to be connected to the filamentary electrode of the discharge lamp and cyclically operable upon the application of a potential thereto and to the discharge lamp to establish a glow discharge in said glow switch with attendant heating of its bimetallic element and movement thereof into contact with the other electrode of said pair to repetitiously complete a starting circuit to the lamp until a discharge occurs therein, and a glow relay disposed in said casing comprising an envelope having a gaseous atmosphere therein and provided with a pair of electrodes one of which is a bimetallic electrode and normally engaging each other to complete a circuit to said glow switch, and having a third electrode for supporting a glow discharge between the latter and said bimetallic electrode simultaneously with the occurrence of a cyclic discharge in said glow switch for heating said bimetallic electrode to cause disengagement thereof from the other electrode of said pair upon continued cyclical operation of said glow switch in a futile attempt to start a defective discharge lamp, and to cause attendant short-circuiting of said glow switch with continuation of the discharge in said glow relay between the bimetallic electrode and said third electrode maintaining disengagement of the normally engaged pair of electrodes thereof until replacement of the defective lamp.
4. A relay unit for starting and operating a discharge lamp provided with a filamentary electrode and for preventing flashing thereof upon such lamp becoming defective comprising a casing, a glow switch disposed in said casing comprising an envelope having a gaseous atmosphere therein and provided with a pair of electrodes one of which is a bimetallic element and adapted to be connected to the filamentary electrode of the discharge lamp and cyclically operable upon the application of a potential thereto and to the discharge lamp to establish a glow discharge in said glow switch with attendant heating of its bimetallic element and movement thereof into contact with the other electrode of said pair to repetitiously complete a starting circuit to the lamp until a discharge occurs therein, and a glow relay disposed in said casing comprising an envelope having a gaseous atmosphere therein and provided with a pair of electrodes one of which is a bimetallic electrode and normally engaging each other to complete a circuit to said glow switch, and having a third electrode for supporting a glow discharge between the latter and said bimetallic electrode simultaneously with the occurrence of a cyclic discharge in said glow switch for heating said bimetallic electrode to cause disengagement thereof from the other electrode of said pair upon continued cyclical operation of said glow switch in a futile attempt to start a defective discharge lamp, and to cause attendant

short-circuiting of said glow switch with continuation of the discharge in said glow relay between the bimetallic electrode and said third electrode maintaining disengagement of the normally engaged pair of electrodes thereof until 5 replacement of the defective lamp, and a resistance in said casing connected in series with one of the discharge supporting electrodes of said glow relay to limit the current in the discharge to cause a slight delay in the disengagement of the bimetallic electrode from the other electrode of said pair until said glow switch has repetitiously operated for a sufficient period of time to start a lamp free from defects.
